UNITED STATES PATENT OFFICE.

PAUL E. COLLINS, OF BOSTON, MASSACHUSETTS, ASSIGNOR, BY DIRECT AND MESNE ASSIGNMENTS, TO ELECTRIC NOVELTY MACHINE COMPANY, OF BOSTON, MASSACHUSETTS, A CORPORATION OF MASSACHUSETTS.

TRANSPARENCY.

No. 873,020.

Specification of Letters Patent.

Patented Dec. 10, 1907.

Application filed December 4, 1904. Serial No. 235,896.

To all whom it may concern:

Be it known that I, PAUL E. COLLINS, a citizen of the United States, residing in Boston, county of Suffolk, and State of Massachusetts, have invented an Improvement in Transparencies, of which the following description, in connection with the accompanying drawings, is a specification, like letters on the drawings representing like parts.

10 The present invention relates to a transparency or illuminated picture, the purpose of the invention being to obtain a novel illuminated effect in which rays of light diverge and converge, after the manner of 15 northern lights, it being practicable, moreover, to obtain certain colored effects at the same time. This is accomplished by interposing between the translucent portion and 20 an illuminating element behind it, a member which has parallel transparent portions, between which the light is obscured by light interfering portions or partially obscured, and causing said member to move from a position in which the lines are in a plane sub- 25 stantially parallel to the plane of the translucent portion to a position in which the lines are in a plane at an angle thereto.

In carrying out the invention, the transparency is illuminated from behind by means 30 of illuminating elements, such as incandescent electric lamps, the globes of which may be striped with coloring matter parallel to their filaments, thereby constituting the imposed members with the parallel transpar- 35 ent portions. These lamps are then caused to rock back and forth on pivots from a position substantially parallel to the face of the transparency to a position at an angle thereto, so that the rays of light will spread 40 radially and then converge, thus giving the effect of northern lights. At the same time, the lights may be controlled by switches, so that the rays will appear and disappear, and lamps of different colors may be differently 45 controlled so that a pleasing effect can be obtained. The lamps may also be arranged radially, although such construction is not essential.

In the construction chosen to illustrate 50 the invention, a series of lamps are shown as pivoted along the periphery of a substantially circular member so as to extend radially therefrom and normally stand paral-

lel to the plane of a suitable transparency which may represent any desired design.

55

The stems upon which the lamps are pivoted are under the control of a rotatable cam against the cam surface of which the lamps are held by springs so that, as the cam revolves, the lamps will rock on their pivots back and forth so as alternately to stand parallel to the plane of the transparency, and at an angle thereto. If, therefore, the globes of the lamps are colored in lines parallel to their axes, so that the light therefrom will appear through the transparency as longitudinal rays, these rays will spread apart and converge as the lamps move away from and towards the surface of the transparency, the effect being substantially the same as that of the play of "northern lights." The effect may further be varied by controlling the current through the several lamps so that they will be alternately lighted and extinguished, and a switch to control the electric circuits may be provided, the switch, preferably, having a series of separate contacts and brushes to control separate lamps having different colored globes. In order to prevent arcing at the contacts, the stationary contact members of the switch, which are shown as arranged in concentric circles, are undercut at the ends where the brushes pass off the contacts, so that the said brushes will quickly snap from the contacts to an insulated base, thereby breaking the circuit so rapidly and with such a large gap that any arc which follows will be ruptured. The cam which controls the movement of the lamps and the contact carrying member of the switch may be operated by a motor common to both, the construction, therefore, being simple and inexpensive.

Figure 1 is a front view of the apparatus 95 with a portion of the transparency broken away to show the illuminating elements and the switch behind; Fig. 2 is a vertical section, on an enlarged scale, of a portion of the device; Fig. 3 is a plan view of the switch on the same scale as Fig. 2; and Fig. 4 is a perspective view, showing a modification.

The transparency *a*, which may be of any suitable or usual type, such, for example, as a painting on glass, is supported in the front 105 of a casing *a*² which contains the illuminat-

ing elements, herein shown as a series of radially arranged incandescent electric lamps b which are shown as pivotally supported at the points b^2 on the disk b^3 which has a stem b^4 extending through the back of the casing. Upon the stem b^4 a cam disk c is rotatably supported, said disk having cam surfaces c^2 against which surfaces the supporting stems b^5 of the lamps bear, the said lamps being held against the cam by means of springs b^6 . If, therefore, the cam disk c is rotated, the lamps b will move back and forth on their pivots from a position parallel to the transparency a to a position at an angle thereto, as indicated in Fig. 2, and if the globes of the said lamps are obscured or partially obscured by light interfering portions parallel to their axes, so as to constitute the interposed members between the light and the transparency, the rays of light shed on the transparency will converge and diverge during the movement of the lamps on their pivots. As herein shown, the globes of the lamps b are provided with opaque or semi-opaque lines which may be of coloring matter, if desired, and the several lamps may be arranged in sets having different colors, in order to vary the effect. In the construction shown, the cam member c is provided with a hub c^3 which is mounted on the stem b^4 and provided with a sprocket c^5 which is driven by a chain c^6 from a suitable motor C , and the same hub may be utilized to carry a sprocket c^7 connected by a chain d with a sprocket on a switch carrying member e .

It is obviously not essential that the interposed members, (in this case the lamp globes) should be arranged on the arc of a circle, or that the operating cam should have a rotary movement. In Fig. 4, for example, a construction is shown in which the members are arranged in a straight line and pivotally supported on a rod b^{20} , the cam surfaces c^{20} being carried on an endless chain c^{10} which is the equivalent of the cam disk c , and which may be driven in any suitable or usual way. The lamps b are held against the cam surfaces by springs b^6 , as in the construction previously described.

As herein shown, the switch carrying member e , driven as above described, by the sprocket c^7 and chain d , is mounted on a spindle secured between a bracket f , and a contact carrying plate g secured to the back of the casing a^2 , the said contact carrying member having a plurality of lines of contact members h , h^2 and h^3 , which may be of varying lengths, according to the effects which are to be obtained. These contact members are arranged in concentric circles, and the switch carrying member e is provided with an arm e^2 having three spring contact members e^3 , e^4 and e^5 arranged to engage respectively with the stationary contact members above described, the said sta-

tionary contact members in turn being connected with rings g^2 , at the back of the member g , which rings are respectively connected with rings b^7 , as by conductors b^8 , the rings b^7 being each electrically connected with part of the lamps b through the springs b^6 which form part of one side of the circuit. The circuit through the lamps starting from the source B , herein shown as a socket plug, is through the conductor 1 to the spindle b^4 which is in electrical contact with one terminal of each lamp, the other terminal of each lamp being in electrical contact with its spring b^6 so that a lamp will be lighted when the proper spring is in contact with one of the members h , h^2 , h^3 , all of the said members being connected with the other side of the circuit through the conductor 2.

In order to prevent arcing as the circuit is broken, the members h , h^2 , h^3 are undercut at the ends where the spring passes off the same, as best shown in Fig. 2, the base g upon which the said contacts are mounted being of insulating material, so that the two contacts are rapidly separated a material distance each time the circuit is broken.

What I claim is:

1. In a transparency, the combination with a translucent design portion; of an illuminating element having opaque portions between said design portion and the luminant movable from a position parallel to the plane of the said translucent portion to a portion at an angle thereto; and continuously operating means for producing such movement of said element.

2. In a transparency, a translucent portion; a series of illuminating elements having opaque portions between said translucent portion and the luminant pivotally supported behind said translucent portion; and a movable member for moving said elements back and forth between positions in which they are respectively substantially parallel to the plane of the translucent portion and at an angle thereto.

3. The combination with a translucent design, of electric lamps provided with globes having stripes of opaque or semi-opaque coloring matter in line with the filaments; and continuously operating means for causing said lamps to travel back and forth between a position parallel to the plane of the design and a position at an angle thereto.

4. In a transparency, a part to be illuminated; means for illuminating the same from the back; a member having parallel stripes of opaque, or semi-opaque, coloring matter pivotally supported between the illuminating means and the part to be illuminated, its pivotal axis being transverse to the stripes, and means for rocking said member on its pivot.

5. In a transparency, the combination

with a translucent design; of a plurality of electric lamps behind said design, said lamps being provided with globes having light interfering portions; a mechanically operated device for producing a bodily movement of said lamps back and forth between a position substantially parallel with the plane of the translucent design at a position at an angle thereto; a traveling switch member to control the circuits of said lamps; and common operating mechanism whereby said me-

chanically operated device and said switch member are caused to operate, substantially as described.

In testimony whereof, I have signed my 15 name to this specification in the presence of two subscribing witnesses.

PAUL E. COLLINS.
